UNITED STATES PATENT OFFICE.

DE LANCY KENNEDY, OF NEW YORK, N. Y.

PUNCHING-MACHINE.

SPECIFICATION forming part of Letters Patent No. 448,525, dated March 17, 1891.

Application filed December 11, 1890. Serial No. 374,306. (No model.)

To all whom it may concern:

Be it known that I, DE LANCY KENNEDY, of the city, county, and State of New York, have invented certain new and useful Improvements in Punching-Machines, of which the following is a specification, reference being had to the accompanying drawings, and to the letters of reference marked thereon.

This invention relates to the means of obtaining and applying a gradually-increasing power in forcing a punch or other tool to its work. In my patent, No. 148,566, dated March 17, 1874, I have shown the application to a lever of what are termed "two rolling cams." In my present invention I have improved upon my former construction by employing two rolling or eccentric toothed cams in connection with a lever whose head is toothed and placed between said cams, one of the cams having a stationary and the other a moving pivot, and the lever being linked to both cams. By such construction increased power and a reduced movement of the operating-lever are obtained.

In the accompanying drawings, Figure 1 is a perspective view of a punching-machine having my present improvement embodied therein. Fig. 2 is a vertical section on the line $\alpha\alpha$ of Fig. 1. Fig. 3 corresponds with Fig. 2 of my Patent No. 148,566. Fig. 4 shows a detail upon a reduced scale.

Similar letters of reference indicate similar parts in the respective figures.

Supposing my invention to be applied to a punching-machine, A is the punch-frame; a, the punching-tool; A', a lever-beam, and A² an operating-lever. The latter may be worked by hand, foot, or power. The lever-beam A' is connected by links b to the sliding punch-holder c.

The punch-frame A is provided with ears a', between which is pivoted by a bolt a² one of the rolling or eccentric-toothed cams C. The long arm of the lever-beam A' is recessed at its end, there being formed ears a³, between which is pivoted a second rolling or eccentric-toothed cam C'. It will be observed by reference to Fig. 4 that the teeth of the lower cam C are upon its inner face, while those of the upper cam C' are upon the outer face. In other words, the toothed faces of the cams are right and left. Between the two cams C C'

is placed the head of the operating-lever A², which is toothed upon its periphery or edge, so as to suitably engage the teeth of the two cams C C'. The operating-lever A² is connected to the two cams C C' by pairs of links d d', the lower pair d connecting the operating-lever with the lower cam C and the pair d' with the upper cam C'. The inner end of the operating-lever A² is united by a pair of links d² to a boss a⁴, formed upon the punch-frame A. The function of the links d, d', and d² as connected to the head of the operating-lever is to furnish said lever with a shifting pivotal point, allowing it to have the proper movement in rolling over or upon the cams C C' in operating the lever-beam A' and the punch or tool to which the latter is connected. The eccentric peripheries of the cams C C' cause a gradually-increasing leverage to be imparted to the lever-beam A'. It will be seen that the contact of the operating-lever A² with the cams C C' is properly maintained by means of the link connections, as described, and that the resistance is borne by the peripheries of the cams and not by the link connections.

This invention is more specially designed for use in machines for punching thin metal, but equally applicable to larger machines, or, indeed, to any machine, whether for punching or otherwise, in which such a concentration of power as is here obtained may be desirable.

Having described my invention, I claim—

1. A frame, a lever-beam, and eccentric-toothed cams, one pivoted to the frame and the other to the lever-beam, combined with an operating-lever whose head is toothed to engage the toothed cams and placed between said cams in operative relation thereto, substantially as described.

2. A frame, a lever-beam, an eccentric-toothed cam pivoted to said frame, and an eccentric-toothed cam pivoted to said lever-beam, combined with an operating-lever having a head toothed to engage the teeth of said cams, and links connecting said operating-lever and cams, substantially as set forth.

3. A frame, a lever-beam, an eccentric-toothed cam pivoted to said frame, and an eccentric-toothed cam pivoted to said lever-beam, the said cams having their teeth ar-

ranged upon opposite sides of their peripheries, combined with an operating-lever having a head toothed upon its periphery to engage the teeth of the cams, links connecting said operating-lever and cams, and links connecting said lever with the frame, substantially as set forth.

4. The combination of a frame, a lever-beam, two eccentric-toothed cams, one pivoted to the frame and the other to the lever-beam, and an

operating-lever having a head toothed to engage said cams and supported in operative contact with and between said cams by a link connection, substantially as set forth.

In testimony whereof I hereto set my hand and seal.

DE LANCY KENNEDY. [L. S.]
